VACUUM PUMP

Carl Freyn, Edinburg, Ind., assignor to Jeanette Lloyd, Indianapolis, Ind.

Application May 6, 1947, Serial No. 746,203

11 Claims. (Cl. 230—171)

1

The present invention relates to a vacuum pump, and more particularly to an extremely simple and inexpensive device which nevertheless is operable to establish a high degree of vacuum. The specific device disclosed and claimed herein is an improvement upon that disclosed and claimed in my prior Patent No. 1,960,902 issued May 29, 1934 for Suction device. The specific structural improvements disclosed and claimed herein for the first time render the device enormously more flexible in use, and are adapted for performing functions of which the device of my prior patent was entirely incapable, all as will appear hereinafter.

The primary object of the present invention, then, is to provide an improved pump capable of application to all sorts of devices for drawing a high degree of vacuum within such devices. A further object of the invention is to provide, for use in association with the said pump, an adapter designed and constructed to withdraw fluids from one container and to transfer such fluids to another container. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a fragmental elevational view of my improved vacuum pump, associated with a bottle to be evacuated;

Fig. 2 is a vertical section through the pump; and

Fig. 3 is an elevational view of the pump, associated with an adapter constructed in accordance with my invention and illustrated in vertical section, the adapter being associated with a container to be evacuated.

In the drawings, the reference numeral 10 indicates generally a pump constructed in accordance with the present invention. As is most clearly illustrated in Fig. 2, one structural feature of the pump is a plug 11 formed of relatively soft, resilient material such as rubber or any of the known rubber substitutes. Said plug preferably assumes the form of an inverted truncated right cone, and at its base, said plug is formed with an extended perimetral flange 12 defining a plane surface 13. Adjacent its base, the plug is preferably provided with a peripheral groove 14.

2

Penetrating the plug and opening through its apex and its base is a passage indicated generally by the reference numeral 15. Said passage comprises an outer section 16 and an inner section 17, the outer section opening through the apex of the plug and into an enlarged cavity 18 intermediate the passage sections, and the inner section opening through the plane surface 13 and into said cavity. Within the cavity is movably mounted a ball valve 19 which, under rest conditions and when the pump is held in the illustrated position, will find a seat upon the mouth of the section 16 opening into the cavity 18 to close communication between the section 16 and said cavity. A short metal tube 20, preferably having a roughened exterior surface, is pressed into the passage section 17, so that one end of said tube lies substantially flush with the surface 13 while the opposite end of said tube projects slightly into the cavity 18. The tube 20 is so sized that it will be frictionally held against displacement by the engagement of the rubber walls of the passage section 17 with the exterior of said tube. That end of the tube 17 which projects into the cavity 18 is notched or slotted as at 21 so that, even if the ball 19 should seat solidly upon the mouth of said tube, fluid may nevertheless flow freely past said ball and through the tube 20.

30 A collapsible dome-shaped body, indicated generally by the reference numeral 22, is formed to provide a chamber 23, and said body may preferably be provided with an integral shank 24 internally threaded as at 25 for the reception 35 of the threaded end 26 of a plunger 27. The chamber 23 is closed except at its open mouth which is bounded by a flexible lip 28, said lip being engageable with the surface 13 to enclose the mouth of the passage section 17 within said chamber. The body 22 may preferably be formed 40 of rubber or any rubber substitute, and is so constructed that, while it may be distorted by downward pressure exerted through the plunger 27, it will tend to return to its illustrated shape, 45 upon release of such pressure, through the inherent resiliency of the body material. The lip 28 is distortable so that, upon collapse of the body 22, fluid contained within said body, and 50 prevented from escape through any other channel, will escape between the lip 28 and the surface 13, by distortion of said lip. The shape of 55 said lip, however, is such that a reduction of pressure within the chamber 23 will not permit air to force its way into said chamber between the lip and the surface 13.

A shroud 29, which may preferably be formed of rubber or any suitable rubber substitute, encloses the body 22 and is formed with a reduced neck 30 through which the plunger 27 loosely extends. At its base, the shroud is formed with an inturned annular lip 31 defining an inwardly opening annular channel 32 adapted to receive and retain the periphery of the flange 12.

If it is desired to evacuate a bottle 33 having a mouth 34, or any other enclosed space having a similar mouth, the plug 11 may be entered in said mouth to establish a sealing relation therewith. Because of the conical shape of said plug, and the resilient character of the material from which it is formed, the plug will, of course, establish a sealing relation with any substantially circular orifice within a wide range of diameters. Such association provides, of course, communication between the interior of the vessel or other closed space, and the interior of the chamber 23, through the passage 15.

Now, the plunger 27 is depressed to collapse the body 22, thereby materially reducing the effective volume of the chamber 23. The air previously entrapped within the chamber 23 must escape therefrom; but the valve ball 19, seated upon the mouth of the passage section 16 prevents air flow out from the chamber 23 through the passage 15. Therefore, the air forces its way between the lip 28 and the surface 13, distorting the lip in passing.

Upon release of the depressing force upon the plunger 27, the inherent resiliency of the body 22 tends to return said body to the shape thereof illustrated in Fig. 2, thereby again enlarging the effective volume of the chamber 23. The pressure within said chamber is thus reduced, to create a pressure differential between the opposite ends of the passage 15 and air from within the vessel 33 or other enclosed space, will rush through said passage 15 into the chamber 23, displacing the valve 19 as it flows. A subsequent collapse of the chamber 22 will force a portion of the air so withdrawn from the vessel 33 out past the lip 28; and repetition of the above cycle will progressively evacuate the vessel 33 or other enclosed space with which the pump is associated.

As the degree of vacuum increases, it may be necessary to exert an upward force upon the plunger 27 to restore the pump body 22 to its illustrated shape. Alternatively, I may incorporate a coiled spring 44 in the organization, preferably embedding one turn of such spring in the neck 24 of the body 22. Where the spring 44 is used, the body 22 need not be made of inherently resilient material, but may be made of canvas or other material suitably impregnate to render it fluid-tight. If desired, the spring 44 may be contoured to correspond with, and embedded in the walls of the body 22.

It may be frequently desirable to provide an organization whereby, through the use of my pump, liquids or gases may be transferred from one container to another. For that purpose, I provide an adapter such as that illustrated in Fig. 3.

In that figure, I have shown a can or other container 35 whose mouth is guarded by a threaded neck 36. My adapter comprises a body 37 which may preferably be formed of rubber or any suitable rubber substitute. The adapter is generally cylindrical, being formed to provide a chamber or passage 43, one open end 38 of which may preferably be threaded for threaded engagement with the container neck 36, and the

other open end 39 of which is tapered for sealing cooperation with the plug 11. Intermediate its ends, the body 37 is formed with a radial port 40 adapted to receive a rigid connector tube 41

5 to which may be connected a flexible conduit 42. It will be clear that, if the remote end of the conduit 42 is dipped into a receptacle containing any fluid, and if my pump is operated in the manner above described, fluid from such receptacle will be transferred to the receptacle 35.

Innumerable uses for the disclosed assembly will at once be apparent. For instance, water will settle to the bottom of an automobile gasoline tank. If the conduit 42 is inserted to the 15 bottom of such a tank, operation of the pump will draw liquid from the bottom of the tank; and all of the water may be thus removed. In such an operation, a transparent receptacle 35 will be used, so that operation can be stopped 20 when it is seen that gasoline, floating on the top of the water first withdrawn from the tank, is being introduced into the receptacle 35. Sludge may be removed from crank cases. Coolant may be temporarily removed from automobile radiators in order to introduce antifreeze solution 25 thereinto, without loss of the original coolant which may contain some antifreeze solution. Liquid fuel may be readily pumped into burner reservoirs. Small receptacles may be readily 30 filled from large reservoirs which large reservoirs are not readily manipulable. Plumbing fixtures may be readily drained, even though they include traps. Foreign matter may be removed from traps. Other uses too numerous to mention will 35 be readily apparent or will occur to the user as he avails himself of the advantages of my pump and adapter.

It will be appreciated that the disclosed pump and adapter may be manufactured of various 40 materials and at extremely low cost, and that there is substantially nothing about the organization to get out of order. Even if any part of the organization should break down after continuous use, such part may be readily replaced 45 without the use of special tools or equipment, and at extremely low cost. With no bearings and substantially no moving parts, I have provided a device whereby a high degree of vacuum may be established in a closed chamber, thereby accomplishing functions not heretofore possible except through the use of relatively expensive and complicated machinery.

I claim as my invention:

1. A vacuum pump comprising a substantially conical plug of yielding material shaped to present a continuous surface at its base, said plug being formed with a passage opening through its apex and through its base, a collapsible body having an open mouth but being otherwise closed 60 to define a fluid chamber, the rim of said body surrounding said mouth being engageable with said continuous surface to enclose the opening of said passage through said base, said rim being flexible to permit the escape of fluid therewith 65 from said chamber, and valve means in said passage operable to prevent fluid flow out of said chamber through said passage.

2. The pump of claim 1 including a spring associated with said body and resiliently resisting collapse of said body.

3. The pump of claim 1 in which said passage is formed, intermediate its ends, with an enlarged cavity, and in which said valve means comprises a valve body movably received in said cavity and engageable with the opening into said cavity of

that portion of said passage remote from said base to prevent fluid flow out of said chamber through said passage.

4. The pump of claim 3 including means co-operable with said valve body to hold said valve body positively out of engagement with the opening into said cavity of that portion of said passage adjacent said base. 5

5. The pump of claim 4 in which said last-named means comprises a rigid tube projected through said adjacent portion of said passage and into said cavity, that end of said tube disposed in said cavity being ported to permit fluid flow therethrough past said valve body when said valve body engages said tube end. 10

6. A vacuum pump comprising a base shaped to provide a substantially continuous surface, said base being imperforate except for a passage opening through said surface, a substantially dome-shaped collapsible body having an open mouth defined by an annular lip, said body defining a chamber closed except at said mouth, said lip being engageable with said surface to enclose said passage opening in said chamber and to seal said chamber against fluid ingress past said lip, said lip being distortable to permit fluid egress from said chamber therewith, and valve means in said passage operable to permit fluid ingress to said chamber therewith but to prevent fluid egress from said chamber therewith. 15

7. The combination with the pump of claim 6 of a shroud element comprising a substantially dome-shaped body adapted to enclose and contain said first-named body, said shroud body being provided with an open mouth surrounded by an annular lip, said lip being formed to provide an inwardly-opening annular seat, the perimeter of said base being receivable in said seat to hold said pump and said shroud element in assembled relation. 20

8. The combination with the pump of claim 1 of an adapter comprising a body shaped to provide an open-ended passage, one open end of said passage being adapted for sealing association with the mouth of a container, the other open end of said passage sealingly receiving said plug, and conduit means opening into said passage intermediate said ends. 25

9. The combination with the pump of claim 1 of an adapter comprising a body shaped to provide a chamber having three ports opening therewith, one of said ports being adapted for sealing association with the mouth of an otherwise closed container to establish communication between the interior of said container and said adapter chamber, another of said ports being tapered for sealing reception of said plug, and conduit means associated with the other of said ports. 30

10. The combination with the pump of claim 1 of an adapter comprising a body shaped to provide a chamber having three ports opening therewith, one of said ports being internally threaded for association with the mouth of an otherwise closed container to establish communication between the interior of said container and said adapter chamber, another of said ports being tapered for sealing reception of said plug, and a flexible conduit communicating with said adapter chamber through the other end of said ports. 35

11. The combination with the pump of claim 1 of an adapter comprising a body formed of rubber or the like and shaped to provide a chamber having three ports opening therewith, one of said ports being adapted for sealing association with the mouth of an otherwise closed container to establish communication between the interior of said container and said adapter chamber, another of said ports being tapered for sealing reception of said plug, and conduit means associated with the other of said ports. 40
